UNITED STATES PATENT OFFICE.

SOLOMON H. BOLTZ, OF PHILADELPHIA, PENNSYLVANIA, ASSIGNOR OF ONE-FOURTH TO
GEORGE H. SMITH, OF PHILADELPHIA, PENNSYLVANIA.

CONTAINER FOR CAKES, CRACKERS, &c.

1,272,903.

Specification of Letters Patent. Patented July 16, 1918.

Application filed May 16, 1917. Serial No. 168,929.

To all whom it may concern:

Be it known that I, SOLOMON H. BOLTZ, a citizen of the United States, residing at Philadelphia, in the county of Philadelphia and State of Pennsylvania, have invented new and useful Improvements in Containers for Cakes, Crackers, &c., of which the following is a specification.

My invention relates to new and useful improvements in containers for cakes, crackers, etc., and has for its object to provide a device of this character which may be readily and clearly inserted in the display can or other receptacle, so that as the top layer of the contents is removed, the lower or underneath layer or layers of the contents may be lifted or raised to a point adjacent the upper or open end of the receptacle so that said receptacle will always have the appearance of being filled thereby making the goods more salable.

Another object of the invention is to provide a device of the character stated having means to limit its elevating movement so as to prevent the contents from being ejected from the receptacle.

A still further object of the invention is to provide a receptacle having a simple inexpensive construction for the application of my improved device, said construction being particularly adapted to the manufacture of new cans which are to embody my invention.

With these ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawings forming a part of this specification, in

45 which—

Figure 1, is a perspective view of a container embodying my invention, a portion thereof being broken away to clearly illustrate the construction.

50 Fig. 2, is an enlarged fragmentary detailed sectional view through the false bot-

tom to illustrate the construction of one of the spring retainers and

Fig. 3, is a plan view of the container showing my invention applied thereto with the cover removed from the container.

In carrying out my invention as herein embodied, 2 represents a container or display can of any ordinary and well known construction, either rigid or collapsible, the upper open end of which is provided with an inturned bead 3, and this upper open end is adapted to be closed by the ordinary display cover 4 having a transparent portion or window 5 of glass or other suitable material.

In the container is placed a false bottom 6 which is adapted to rest directly upon the bottom of the container, and this false bottom is provided with a plurality of projections 7 or spring retainers, and these are preferably formed integral with the false bottom, the same being stamped therefrom. These spring retainers are preferably circular in cross section, and each has a hole 75 or passageway 8 therethrough.

A coil spring 9 is attached to each of the spring retainers 7 by placing one end of the spring over the projection with the end of the wire forming the spring disposed 80 across the diameter of the spring and inserted through the hole or passageway 8 in the projection 7.

Within the container is a partition or tray 10 having the edges turned downward or inward to produce a flange 11 and said tray is provided with a plurality of projections 7, each having a hole or passageway 8 therethrough similar to the projections formed with the false bottom. The upper 90 ends of the springs are attached to the projections formed with the tray and in actual practice, I have found it advisable to use four springs, one for each corner of the tray.

95 The projections of the false bottom 6 extend upwardly, while the projections of the tray 10 extend downwardly in alinement with each other, so that when the tray is depressed to its lowest point, the projections 100 contact with each other and limit the downward movement of the tray, leaving them

spaced apart sufficiently to accommodate the length of the compressed springs.

When the container is being packed, a sheet 12 of suitable material, such as paper or cardboard is placed upon the upper or outer face of the tray 10, and the contents are placed directly thereon, providing a lowermost layer, some of which are separated from the others by transverse vertical separators 13, and at two opposite sides of the container in contact with the side walls of said container and resting upon the tray 10 are situated a pair of oppositely disposed adjusting strips 14 of any suitable material, such as cardboard.

On top of the lowermost layer of the contents is then placed a horizontal separator 15 which is the same as the sheet 12, and is of the same material, after which the lower layer of contents and the tray 10 with the separators are pushed down into the can against the action of the springs 9, and another pair of adjusting strips 14 are placed against the sides of the container resting upon the horizontal separator and underlying the beads 3 at two opposite sides. The packing of the container is continued in the same manner until it is completely filled, after which a cover is placed thereon.

30 When the container is used as a dispensing can, the upper layer of cakes, crackers or other contents is removed, and when all of them have been sold or taken out, the adjusting strips 14 are removed which will permit the springs to act and force the tray 10 and the objects supported thereby upward until one of the separators 15 contacts with the bead of the container, after which said separator may be removed to uncover 40 and display the next layer of contents, and when said separator is removed, the adjusting strips 14 will engage the beads 3 of the container and prevent said springs from ejecting the contents, and when all of the 45 contents and all of the adjusting strips are removed, the tray 10 will engage the beads of the container, so as to prevent the springs from projecting the tray beyond the upper edge of the container. The separators 15 50 may be provided with any suitable means for removing the same, and in practice I have found that the preferred way is to provide each of the separators with finger holes 16 in which the thumb and forefinger may 55 be inserted.

Where, as above described, the false bottom, tray and springs are made separately, there is provided a contents elevator which may be applied to old cans or those at present in use. The false bottom and tray are made narrower in one direction than the space between two oppositely disposed beads formed with two opposite walls of the container, so that the contents elevator will 65 readily pass two oppositely disposed beads

of the container leaving a space 19 between them as plainly shown in Fig. 3.

The width or length of the false bottom and tray in the opposite direction is sufficient to snugly fit the container, and underlying the beads at two oppositely disposed sides of said container.

In placing the contents elevator in the container, the same is tilted to one side, and the lower edge is inserted in the container and forced downward a sufficient distance for the opposite edge to pass under the opposite bead, after which the contents elevator may be straightened up and two of the oppositely disposed edges will project beneath two oppositely disposed beads, so as to permit the use of the adjusting strips 14.

Where the device is used with a collapsible retainer or receptacle, the springs may be removed from the parts to which they are attached, so as to disassemble the contents elevator, whereby it will occupy an exceedingly small amount of space.

The bottom of the receptacle or container is provided with a hole 18 for an admission 90 of air to permit the ready elevation of the tray 10, and also for the expulsion of air when the container is being packed.

Of course I do not wish to be limited to the exact details of construction as herein 95 shown, as these may be varied within the limits of the appended claims without departing from the spirit of my invention.

Having thus fully described my invention, what I claim as new and patentable 100 is—

1. In a device of the character stated, the combination with a receptacle having an open end and provided with an inturned bead at said open end, and a false bottom within the container and resting on the bottom thereof, a tray slidably mounted in the container, springs arranged between the false bottom and said tray for normally 105 forcing the latter toward the open end, separators arranged above the tray and adjusting strips adapted to coact with the tray and the separating strips and the beads on the container for adjusting the position of the tray.

2. In a device of the character stated, the combination with a container having an open end and provided with an inturned bead around said open end, a false bottom narrow enough to pass two opposite beads and long enough to project under the two oppositely disposed beads, a tray narrow enough to pass two of the opposite beads and a sufficient length to project beneath the other two oppositely disposed beads, a down turned flange formed with the edge of said tray, springs disposed between the false bottom and said tray for normally forcing the latter outward, separators arranged above the tray and means coacting with the tray 110 120 125 130

and certain of the separators and the oppositely disposed beads under which the ends of the tray project for adjusting the positions of the tray within the container.

5 3. In a device of the character stated, the combination with a container having an open end and provided with an inturned bead around said open end, a false bottom narrow enough to pass two opposite beads and 10 long enough to project under the two oppositely disposed beads, a tray narrow enough to pass two of the opposite beads and a sufficient length to project beneath the other two oppositely disposed beads, a down 15 turned flange formed with the edge of said

tray, projections formed integral with the false bottom and tray, coil springs having their ends projecting across the coils thereof, said springs adapted to surround the projections with the ends of said springs passing through said projections, separators disposed above the tray and means coacting with the tray, certain of the separators and certain of the beads to hold the tray in certain adjusted positions relative to the open 25 end of the container.

In testimony whereof I have hereunto affixed my signature.

SOLOMON H. BOLTZ.
